UNITED STATES PATENT OFFICE.

JAMES W. MCLEAN, OF ST. LOUIS, MISSOURI; LEE A. MCLEAN ADMINISTRATOR OF SAID JAMES W. MCLEAN, DECEASED.

FIRE-SCREEN GATE.

SPECIFICATION forming part of Letters Patent No. 698,848, dated April 29, 1902.

Application filed June 28, 1901. Serial No. 66,444. (No model.)

To all whom it may concern:

Be it known that I, JAMES W. MCLEAN, a citizen of the United States, residing in the city of St. Louis, State of Missouri, have invented a new and useful Fire-Screen Gate, of which the following is a specification.

My invention relates to an improvement in fire-screens in which said fire-screens are provided with hinges and a lock and the fire-frame with hinging and locking members, as is hereinafter described; and the objects of my improvement are, first, to hang a fire-screen gate on a fire-frame without marring the front of the frame or mantel; second, to have the fire-screen gate always locked when in closed position, and, third, to provide a new, safe, and convenient handling of a fire-screen in the form of a gate. These objects are attained by attaching a fire-screen gate to an open fireplace, as illustrated in the accompanying drawings, in which—

Figure 1 shows the elevation of an open fire-frame having hinge members and a lock-catch. Fig. 2 is a detail perspective showing hinges with elbowed arms, indentation of the rim of the screen, bolts and nuts, and manner of affixing hinges to screen. Fig. 3 is an elevation view of a fire-screen mounted on arm and elbow hinges and carrying a lock. Fig. 4 is a detail perspective showing the points of the frame on which hinge members are affixed. Fig. 5 is a multiple view of an elevation, partly in section, showing the several parts of the lock. Fig. 6 is an elevation view of the lock in closed position. Fig. 7 is a front elevation of a fireplace, showing fire-screen gate closed and locked; and Fig. 8 is a detail perspective showing the lock-plate affixed within the indentation of the screen.

The fire-frame D, Fig. 1, is provided with hinge members *h h* and a lock-catch *v*. The hinge members are perpendicularly bored for threaded bolts *m m*, Fig. 2, and flat side up protrude from the left wall *y* of fireplace. These members *h h* are united to the back side of frame D at *o o*, Fig. 4, which sends them back into the fireplace as far at least as the thickness of the frame at its fire edge *x*, Fig. 4. The lock-catch *v*, Fig. 1, protrudes flat side front from the right wall *y* of fireplace. In the manner of hinge members *h h*

lock-catch *v* is united to the back side of frame D at *p*, Fig. 1, and also sent back into the fireplace as far as the thickness of frame shown at *x*, Fig. 4. Catch *v* is not bored. 55

The hinges A B, Fig. 2, are constructed with two leaves each, an upper leaf *a a* and a lower leaf *b b*, which are held and made inseparable by pivot-pins *c c*, upon which the lower leaf *b* of hinge A and the upper leaf *a* of hinge B turn. These two leaves *b* and *a* are united to the screen C at *d d*, Fig. 2, and owing to their shape carry the screen away from frame D when the screen is swung open. The upper leaf *a* of hinge A and the lower 60 leaf *b* of hinge B are made with arms *e e*, which are crooked by elbows *g g*. At the end of arms *e e* bored flanges *l l* protrude from the lower edges of *e e* and will rest upon the upper side of hinge members *h h* when bolted 70 thereto. From elbows *g g* to flanges *l l* arms *e e* may be any necessary length, and in width will conform to the thickness of their hinge-leaves. Hinges A B being united to screen C at *d d*, the arms *e e* pass under an indentation of the rim of the screen at *f f*, Fig. 2, and are carried by elbows *g g* around the fire edge *x* of the frame D, Fig. 4. Flanges *l l* of arms *e e* are then connected with the upper sides of bored hinge members *h h* at *o o*, Fig. 4, and 75 are made fast with threaded bolts *m m* and nuts *s s*, Fig. 2. The hinges are thus brought into action in front of the fire-frame, although hung from hinge members *h h* on left wall *y* within the fire-place. This manner of hanging the screen-gate insures against defacement of the frame or mantel and leaves no 80 hinge or locking members in sight when the screen is taken down and the fire-front put up for the summer. 90

In the construction of the lock in Fig. 5 knob E is made with a square hollow extension or handle *b'*, which extends into the knob, as shown at *c'*. Each side of the open end of the hollow handle *b'* has a small threaded 95 boring *b''*, as shown in Fig. 5, to receive a screen, the boring running horizontally with the handle. The size of the boring depends on the thickness of the metal. At the end *c'* of hollow handle *b'* a cavity *d'* as deep as the thickness of the metal extends across the floor or lower side of handle *b'*, as shown in 100

the exposed view of the inner parts of knob E. A pin g' , affixed to a push-button f' , extends up through an aperture h' in knob E and passes into a perforation h' of the lower side of handle b' at c' . The second part of the lock consists of two steel prongs $l' l'$, having flanges $m' m'$, made in one piece and bent in the form shown in drawings. The prongs must be thin enough to provide an easy spring 10 when pressure is brought to bear upon them. Precisely in the center of the curve at n' a steel rod p' is firmly affixed. This rod extends toward the flanges $m' m'$, and at r' will be the thickness of lock-catch v short of the 15 length of prongs $l' l'$ when flanges $m' m'$ are brought together. A rod t' , having a tumbler s' , is pivoted at u' , so that the tumbler will easily fall into cavity d' of handle b' . Rod t' has an overhanging edge s'' at tumbler 20 s' to catch the pin g' when button f' is pushed. A guard v' , made in the form of the letter H and perforated at $v^2 v^2 v^3$, has a cross-piece w' , supporting upper side guards $x' x'$ and lower side guards $x'' x''$. Guard v' covers the 25 open end of handle b' and is made to permit the prongs $l' l'$ to work in. The upper and lower side guards $x' x''$ and cross-piece w' will thus keep the prongs $l' l'$ in place when inserted into the handle b' and prevent the 30 handle from slipping out of the plate y' when the lock is open.

The screen C is indented at $z' z'$, at which points a lock-plate y' is affixed firmly to the screen and its rim. The plate y' is provided 35 with an aperture z'' . On the front side of the plate the aperture is rimmed to steady handle b' and is made to permit the handle to slide in without too much freedom.

Having thus described the construction of 40 the several parts of the lock, a further exposition will show how they are brought together. The plate y' , Fig. 5, is firmly united to the screen and its rim at the points z' , the indentation of the screen permitting the plate 45 to present a flat front. The handle b' is inserted into the aperture z'' , and the prongs $l' l'$ are then inserted into the hollow of handle b' and held in place by guard v' , which is passed over rod p' , through perforation v^3 , and 50 screwed to the handle at threaded borings b'' and perforations v^2 . This unites the lock in an open position to the screen. To close the lock, the screen is swung against the fire-frame D at p , Fig. 1, which brings the end r' 55 of rod p' , Fig. 5, against the flat or front side of lock-catch v of frame D. Thus is formed

a point of resistance against which the handle b' is pressed, the result being that as rod p' can go no farther the handle b' is pushed upon the prongs $l' l'$ until the tumbler s' falls 60 into cavity d' in handle b' , which happens when the handle is pushed far enough upon the prongs to bring the flanges $m' m'$ together on the other side of catch v . This act locks the screen, as in Fig. 7, and holds the lock F 65 securely closed, as in Fig. 6, by the tumbler s' being in cavity d' , the point r' of rod p' being against the near side of lock-catch v and the flanges $m' m'$ having been brought together on the far side of catch v . To release 70 the lock, the button f' in knob E is pressed upward, which sends the pin g' through the perforation h' in handle b' and against the overhanging edge s'' of rod t' , thereby raising the tumbler s' out of cavity d' and allowing 75 handle b' to be pulled off the prongs $l' l'$, thus opening the lock and releasing the screen-gate from its locked position.

I am aware that fire-screens are in general use and have been mounted in different 80 forms; but I am not aware that the combination as herein set forth has ever been used.

What I claim as my invention, and desire to secure by Letters Patent, is—

1. The combination, in a fire-screen gate, of 85 a fire-frame having hinge members $h h$, and lock-catch v , affixed to the back side of the frame at the fire edge, a fire-screen mounted on arm and elbow hinges A B, to be united to the hinge members on the frame, the arms 90 e e and elbows g g affixed to said hinges an indented rim for the passage of hinge-arms, and the lock F affixed to the screen to coöperate with the lock-catch on the frame, all substantially as set forth. 95

2. A fire-screen gate comprising a catch and a hinged screen having an indentation, a lock-plate therein, a lock having a knob carrying a pin and push-button, a hollow handle affixed to the knob, spring members and a 100 stop member, movable within said handle and having a rod and tumbler to be operated by said push-button, said spring members coöperating with the catch above mentioned; all substantially as shown. 105

In testimony whereof I have signed my name to this specification in the presence of two subscribing witnesses.

JAMES W. MCLEAN.
